DESIGN FOR A COAT

Salvatore Lo Prete, New York, N. Y.

Application October 16, 1940, Serial No. 95,862

Term of patent 3½ years

To all whom it may concern:

Be it known that I, Salvatore Lo Prete, a citizen of the United States of America, residing in New York city, county of New York, and State of New York, have invented a new, original, and ornamental Design for a Coat, of which the following is a specification, reference being had to the accompanying drawing, forming part thereof, wherein,

I claim:

The ornamental design for a coat, substantially as shown.

SALVATORE LO PRETE.
